CLAIM

The ornamental design for a chevron tool jaw, as shown and described.

DESCRIPTION

FIG. 1 is a top, front, left side perspective view of a chevron tool jaw, showing my new design;

FIG. 2 is a bottom, rear, right side perspective view thereof;

FIG. 3 is a top plan view thereof;

FIG. 4 is a left side elevational view thereof;

FIG. 5 is a front elevational view thereof; and,

FIG. 6 is a top, front, left side perspective view thereof.

The broken lines are included for the purpose of illustrating portions of the chevron tool jaw and form no part of the claimed design. The additional broken lines of FIG. 6 are included for showing environmental structure and form no part of the claimed design.
